UNITED STATES PATENT OFFICE

120,224

DESIGN FOR A NEGRO MAMMY DOLL

Inez O. King, Russellville, Ark.

Application January 12, 1940, Serial No. 89,436

Term of patent 3½ years

To all whom it may concern:

Be it known that Inez O. King, a citizen of the United States of America, residing at Russellville, in the county of Pope and State of Arkansas, has invented a new, original, and ornamental Design for a Negro Mammy Doll, of which the following is a specification, reference being had to the accompanying drawing, forming part thereof.

I claim:

The ornamental design for a negro mammy doll, as shown.

INEZ O. KING.
